CHARLES K. BROWN, OF TROY, NEW YORK, ASSIGNOR TO HIMSELF, CHARLES A. BROWN, AND FRANKLIN FIELD, OF SAME PLACE.

Design No. 3,115, dated July 21, 1868.

DESIGN FOR A SHIRT-COLLAR.

The Schedule referred to in these Letters Patent and making part of the same.

TO ALL WHOM IT MAY CONCERN:

Be it known that I, CHARLES K. BROWN, of the city of Troy, in the county of Rensselaer, and State of New York, have invented or produced a new and original Design for a Turned-Over Paper Collar, of which the following is a full, clear, and exact description, reference being had to the accompanying photograph of a turned-over paper collar having my said design.

My new design for a turned-over paper collar relates only to the outline shape of the front ends of the turned-over portion, and can be distinguished from all others by the lower part of each front end of the turned-over portion, C, of the collar being apparently cut off, so as to form two corners, a b, b a, and present the appearance represented in the aforesaid photograph.

What I claim as my invention, and desire to secure by Letters Patent, is—

The design or shape for the ends of the turned-over portion of a paper collar, herein set forth and shown by the accompanying photograph.

In testimony whereof, I hereunto set my hand, this 8th day of May, 1868.

CHARLES K. BROWN.
